UNITED STATES PATENT OFFICE

JOHN F. EAKINS, OF EVANSTON, ILLINOIS, ASSIGNOR TO STANDARD OIL COMPANY, OF WHITING, INDIANA, A CORPORATION OF INDIANA

PREVENTION OF EVAPORATION LOSSES

Application filed July 2, 1927. Serial No. 203,114.

This invention relates to the prevention of evaporation losses from volatile liquids, and particularly from hydrocarbon or mineral oils containing volatile fractions.

5 The invention will be readily understood from the following description, in which:

Figure 1 is a sectional view of a valve and associated operating mechanism, for controlling the admission of gases and vapors to a liquid storage system;

10 Fig. 2 is a sectional view on the line 2—2 of Fig. 1;

Fig. 3 is a sectional view on the line 3—3 of Fig. 1;

15 Fig. 4 is a sectional view of a valve assembly similar to that shown in Fig. 1, associated with a valve and operating mechanism for controlling the escape of gases and vapors from a storage system; and

20 Fig. 5 is an elevation of a general apparatus embodying the valve assembly shown in Fig. 4.

Referring to the drawings, 10 is a chamber into which leads a conduit 11 from the vapor 25 space of a liquid storage system. The chamber 10 is provided with a vertical outlet 12 around which is constituted a sealing liquid channel 13 by exterior walls 14. An inverted cup 15 is provided, said cup having a depending skirt 16 which is adapted to extend into the sealing liquid in the channel 13. The inverted cup is provided with means normally tending to maintain it in an elevated position. As shown in the drawings, this means may 35 take the form of an air chamber or float 17, preferably located around the lower edge of the skirt 16 so that the buoyancy thereof will exert a constant upward force during all or substantially all positions of the inverted cup. The walls 14 preferably terminate in a flange 18 and a cover 19 is provided having a flange 20 adapted to co-operate with the flange 18. The cover 19 is perforated, as shown at 21, so that the upper side of the inverted cup 15 is subjected to atmospheric 40 pressure. The cover 19 is constructed so as to permit sufficient movement of the inverted cup 15 for a purpose which will hereinafter appear.

50 Within the chamber 10 is provided a hori-

zontal open mouth 22 which leads into a conduit 23 which is adapted to be connected to a pressure line 24 whereby gases and vapors may be supplied into said chamber. The mouth 22 is surrounded by a channel 25 adapted to receive sealing liquid, and is provided with a cylindrical valve 26 pivoted about its axis, at 27, and having depending skirts adapted to be immersed in the liquid in the channel 25 for the purpose of forming a 60 liquid seal when the valve is in its closed position, as shown in Fig. 1. The valve 26 is weighted, as shown at 28, so as to tend to maintain said valve open.

A cord 29 extends from the underside of the inverted cup 15 and is attached to the valve 26 near the weight 28, or other suitable point. A grooved wheel 30, suitably mounted in the chamber above the valve 26, is provided for the purpose of guiding the cord 29.

The float 17 or other means which may be employed for imparting an upward force to the inverted cup 15, is designed or regulated so as to permit a certain predetermined degree of subatmospheric pressure in the chamber 10 before the valve 26 opens. For example, in dealing with gasoline tanks of great size, it is necessary to avoid a pressure difference of more than, say, one-tenth of an inch of water between one side of the tank roof and the other. It is obvious that by adjusting the size of the float 17 or the weight 28, in conjunction with the mass of the cup 15, it is possible to insure the opening of the valve 26 when the excess pressure of the atmosphere 80 attains that amount.

The valve structure hereinbefore described may suitably be combined with the valve structure described and claimed in the application of Harold V. Atwell, Serial No. 180,321, filed April 1, 1927. This combination is illustrated in Fig. 4, in which the right-hand side shows the valve and associated parts hereinbefore described, the same reference numerals being applied to designate the same parts. On the left-hand side is shown the valve described and claimed in the application above referred to. This structure is located in the same chamber 10 which is provided with a vertical outlet 31

corresponding to the vertical outlet 12. The outlet 31 is surrounded by a sealing liquid channel 32 which may communicate with the channel 13. The cover 19 may be common to both valves. The vertical outlet 31 is closed by an inverted cup 33, similar to the inverted cup 15, but unprovided with a float or other means normally tending to force same into an elevated position.

10 A horizontal mouth 34 opens into the chamber 10, said mouth leading into a conduit 35 which is adapted to be connected to a vacuum line 36. The horizontal mouth 34 is provided with a cylindrical pivoted valve 37 adapted to co-operate with sealing liquid in a surrounding channel 38. The valve 37 is similar to the valve 26, but is provided with a weight 39' adapted to tend to maintain it in the closed position. The underside of the inverted cup 33 is connected to the valve 37 by a cord 39 which passes over a grooved wheel 40, said cord being attached to the valve 37 near the weight 39'.

15 The weight and area of the cup 33 and the weight 39' are so designed or adjusted that the valve 37 is opened when the pressure in the chamber 10 exceeds atmospheric by the excess pressure permissible in the storage tanks, for example, one-tenth of an inch of water.

20 The installation of the combined valve assemblage just described in a typical storage system is shown in Fig. 5 in which 41 are petroleum storage tanks, the vapor spaces of which are connected by pipe 11 to the chamber 10. A gas-holder 42 is provided for the storage of gases and vapors. The pressure line 24 communicates with the gas-holder and is connected to the conduit 23 which is controlled by the valve 26. The vacuum conduit 36 is connected to the suction side of a pump 43, which may be operated continuously or intermittently to maintain a low pressure in line 36 and to pump gases and vapors therefrom by line 44 into gas-holder 42. It must be understood that the gas-holder 42 is merely shown by way of example, since the lines 44 and 24 may be connected to any other suitable apparatus for the reception and supply, respectively, of gases and vapors.

25 The operation of the valve assembly shown in Figs. 1 to 3, and on the right-hand side of the chamber 10 in Figs. 4 and 5, is as follows: Assuming atmospheric or somewhat higher pressure in the vapor spaces of the tanks 41, then the inverted cup 15 under the buoyancy of float 17 is in its elevated position, as shown in Figs. 1 and 2. If the pressure in the vapor space in the tanks 41 decreases to the predetermined minimum below atmospheric, for example one inch of water below said pressure, the excess pressure of atmosphere acting on the upper side of the inverted cup 15, together with action of the weight 28, is sufficient to overcome the buoyancy of the float

17 so that the valve 26 opens and the parts move into the position shown on the right-hand side of Fig. 4. When this happens gases and vapors pass from the pressure line 24 into the chamber 10 and from there they proceed by line 11 into tanks 41 thereby preventing excess vacuum therein. When the pressure in said tanks becomes higher than the safe minimum, the valve 26 is closed again.

25 The valve 37 and associated parts in the left-hand side of the chamber 10, as shown in Figs. 4 and 5, operate as described in the aforesaid application. That is, when the pressure in the vapor spaces of tanks 41 exceeds atmospheric by a predetermined amount, for example, by one inch of water, said excess of pressure is exerted upon the underside of the cup 33, moving it upwards and opening the valve 37. Thereupon gases and vapors pass into the vacuum line 36 and are withdrawn therefrom by pump 43 and fed through line 44 into the gas-holder 42 until the pressure in the tanks 41 is reduced below the safe predetermined maximum pressure, whereupon the inverted cup 33 descends and the valve 37 closes again.

30 It is to be noted particularly the valves 26 and 37 being cylindrical in form and pivoted axially, are unaffected by the difference of pressure on one side or the other, and their opening and closing is effected primarily by the difference of pressure in the tanks 41 and the atmospheric pressure exerted upon the inverted cups 15 and 33.

35 Although the present invention has been described in connection with the details of specific embodiments thereof, it is not intended that such details shall be regarded as limitations upon the scope of the invention, except in so far as included in the accompanying claims.

40 I claim:

1. A valve structure comprising a chamber, a conduit leading into said chamber, an outlet from said chamber, vertical walls around said outlet forming a channel for sealing liquid, an inverted cup over said outlet having a skirt depending into said channel, means adapted to maintain said cup in an elevated position except when subjected to a predetermined excess of pressure on its exterior, a second outlet from said chamber, a valve controlling said second outlet, and means connecting said inverted cup to said valve to effect operation thereof from the movement of the inverted cup.

45 2. A valve structure comprising a chamber, a conduit leading into said chamber, an outlet from said chamber, vertical walls around said outlet forming a channel for sealing liquid, an inverted cup over said outlet having a skirt depending into said channel, a float adapted to maintain said cup in an elevated position except when subjected to a

- predetermined excess of pressure on its exterior, a second outlet from said chamber, a valve controlling said second outlet, and means connecting said inverted cup to said valve to effect operation thereof from the movement of the inverted cup.
3. A valve structure comprising a chamber, a conduit leading into said chamber, an outlet from said chamber, vertical walls around said outlet forming a channel for sealing liquid, an inverted cup over said outlet having a skirt depending into said channel, means tending to maintain said cup in an elevated position, conduit means extending partially into said chamber so as to constitute therearound a channel for sealing liquid, a pivoted valve over said conduit with sides extending into said channel, means connecting said inverted cup to the pivoted valve so as to effect rotation and opening of same when the inverted cup is moved inwardly by excess of atmospheric pressure over the pressure in the chamber.
4. A valve structure comprising a chamber, a conduit leading into said chamber, an outlet from said chamber, vertical walls around said outlet forming a channel for sealing liquid, an inverted cup over said outlet having a skirt depending into said channel, a float tending to maintain said cup in an elevated position, conduit means extending partially into said chamber so as to constitute therearound a channel for sealing liquid, a pivoted valve over said conduit with sides extending into said channel, means connecting said inverted cup to the pivoted valve so as to effect rotation and opening of same when the inverted cup is moved inwardly by excess of atmospheric pressure over the pressure in the chamber.
5. A valve structure comprising a chamber, a conduit leading into the side thereof, an outlet extending upwardly from the top of said chamber, vertical walls around said outlet and in spaced relation thereto forming a channel for sealing liquid, an inverted cup having a depending skirt extending into said channel, means tending to maintain said cup in an elevated position, a conduit leading into the bottom of said chamber and extending thereinto so as to constitute a channel for sealing liquid therearound, a pivoted valve member having sides which extend into said channel, means normally tending to open said valve, and flexible means connecting said inverted cup to said valve member so that downward movement of the inverted cup permits rotation and opening of said valve and upward movement of said cup effects the closing of said valve.
6. A valve structure comprising a chamber, a conduit leading into the side thereof, an outlet extending upwardly from the top of said chamber, vertical walls around said outlet and in spaced relation thereto forming
- a channel for sealing liquid, an inverted cup having a depending skirt extending into said channel, means tending to maintain said cup in an elevated position, a conduit leading into the bottom of said chamber and extending thereinto so as to constitute a channel for sealing liquid therearound, a pivoted valve member having sides which extend into said channel, a weight on said valve normally tending to open same, and flexible means connecting said inverted cup to said valve member so that downward movement of the inverted cup permits rotation and opening of said valve and upward movement of said cup effects the closing of said valve.
7. A valve assembly comprising a liquid sealed inverted cup subjected to atmospheric pressure on one side and a variable vapor pressure on the other, a pivoted cylindrical liquid sealed valve adapted to close a vapor conduit, means normally tending to open said valve, and means connecting said valve and cup to cause same to operate in unison.
8. A valve assembly comprising a liquid sealed inverted cup subjected to atmospheric pressure on one side and a variable vapor pressure on the other, a pivoted cylindrical valve adapted to close a vapor conduit, a weight on said valve normally tending to open same, and flexible means connecting said valve and cup to cause same to operate in unison.
9. A valve assembly comprising a pair of liquid sealed inverted cups subjected to atmospheric pressure on one side and a variable vapor pressure on the other, a pair of pivoted cylindrical valves adapted to close a pair of vapor conduits, flexible means connecting each cup to a valve so as to cause each valve to operate in unison with a cup, means for exerting a force on one of said cups in the same direction as the effect of the vapor pressure, means on the valve associated with said cup tending to open same, and means on the other valve tending to close same.
10. A valve assembly comprising a pair of controlling members subjected on one side to atmospheric pressure and on the other side to a variable vapor pressure, means adapted to exert force on one of said members in the same direction as the effect of said vapor pressure, a pair of valves controlling vapor conduits and connected to said members so that one valve opens when the atmospheric pressure exceeds said vapor pressure by a predetermined amount and the other opens when said vapor pressure exceeds atmospheric pressure by a predetermined amount.
11. A valve structure comprising a chamber, a conduit leading into said chamber, a pair of outlets from said chamber, vertical walls around said outlets forming channels for sealing liquid, a pair of inverted cups over said outlets having skirts depending into said channels, a float tending to main-

tain one of said cups in an elevated position, a pair of conduits leading from said chamber, valves controlling said conduits, means connecting each inverted cup to a valve to effect operation thereof from the movement of the inverted cup.

12. A valve structure comprising a chamber, a conduit leading into said chamber, a pair of outlets from said chamber, vertical walls around said outlets forming channels for sealing liquid, a pair of inverted cups over said outlets having skirts depending into said channels, means tending to maintain one of said cups in an elevated position, a pair of conduits extending partially into said chamber so as to constitute channels for sealing liquid, pivoted valves over said conduits with sides extending into said channels, means connecting said inverted cups to the pivoted valves so as to effect rotation and opening of one valve when the corresponding inverted cup is moved outwardly by excess of pressure in the chamber over atmospheric pressure and the rotation and opening of the other valve when the corresponding inverted cup is moved inwardly by excess of atmospheric pressure over the pressure in the chamber.

13. A valve structure comprising a chamber, a conduit leading into said chamber, an outlet from said chamber, vertical walls around said outlet forming a channel for sealing liquid, an inverted cup over said outlet having a skirt depending into said channel, means adapted to maintain said cup in an elevated position, except when subjected to a predetermined excess of pressure on its exterior, a second outlet from said chamber, a valve in said chamber controlling said second outlet, and means connecting said inverted cup to said valve to effect operation thereof from the movement of the inverted cup.

JOHN F. EAKINS.
